UNITED STATES PATENT OFFICE.

WILLIAM J. KNITTER, OF NORTH TONAWANDA, NEW YORK.

CLOTHESLINE FASTENER.

Application filed March 6, 1924. Serial No. 697,227.

This invention relates to improvements in clothes line fasteners.

The principal object is to provide a clothes line fastener by which the line can be tightened so that it will not require clothes poles or other intermediate supports to prevent it from sagging.

Further objects are to provide a device which may be readily manipulated for the purpose of tightening or slackening the clothes line, which may be readily changed from one place of support to another, and which may be economically produced.

An embodiment of the invention is illustrated in the accompanying drawing, wherein:

Figure 1 is a side elevation showing a construction which, as now considered, is preferred.

Figure 2 is a front elevation of the same.

Figure 3 is a sectional view on the line 3—3 of Figure 1.

Figures 4 and 5 are sectional views on the respective lines 4—4 and 5—5 of Figure 2.

The device includes a supporting bracket 1 having parallel upper and lower horizontal arms 2 and 3 and provided beyond the arms with attachment extensions 4 and 5, the extension 4 having an L-shaped recess 6 which opens at one side of said extension and the extension 5 having a vertical recess 7 open to its lower edge. The bracket 1 may be supported by any suitable stationary part, the means of support comprising upper and lower bolts 8 and 9, the upper bolt engaging in the recess 6 and the lower bolt engaging in the recess 7. In securing the bracket to its support the horizontal part of the recess 6 is aligned with the bolt 8 and the bracket is shifted laterally until its further movement is arrested by the engagement of the bolt 8 against the vertical side of said recess; at such time the bolt 8 will be in alignment with the vertical part of the recess 6 and the bolt 9 will be in alignment with the recess 7; the bracket is then lowered to complete the engagement of said bolts in the recesses 6 and 7. To remove the bracket from the support the bracket is first raised, thereby to disengage the bolt 9 from the recess 7 and then shifted laterally, thereby to disengage the bolt 8 from the recess 6. Bracket supports may be arranged at any desired places, both inside and outside the dwelling, and the bracket may, by proceeding as above indi-

cated, be readily changed from one location to another accordingly as it may be desirable to change the place where the clothes are to be hung for drying.

The line to be held is connected at one end 60 to a vertical drum 10 which is arranged between the arms 2 and 3 and is provided with a pair of laterally projecting posts 11 to which the end of the line L is secured in any suitable manner. In the construction shown 65 the drum 10 is fitted upon a centrally located rod 12 which projects at both ends beyond said drum and has a bearing at 13 in the upper arm 2. The drum 10 is rotated by means of a driver 14 located below the 70 arm 3 and having a hub portion for which the arm 3 provides a bearing, the driver 14 having coupling pins 15 projecting upward from its hub portion for driving fit engagement in recesses in the under face of the 75 drum. The driver 14 is provided with an opening through which the rod 12 projects and is engaged from below by a nut 16 mounted upon a threaded axial extension 17 of said rod. The driver 14 is provided with 80 a suitable number of radially arranged openings 18 in any one of which the rod 19, which serves as an operating handle, may be removably inserted.

The drum 10 is held against retrograde 85 movement by the co-operation of a pawl 20 with ratchet teeth 21. In the construction shown the ratchet teeth 21 are formed in annular series in the under face of the arm 2 and the pawl 20 is in the form of a rod 90 slidably mounted in a longitudinal opening in the drum 10. The pawl 20 is held engaged with the ratchet teeth 21 by a spring 22 which at its lower end bears against the hub of the driver 14 and at its upper end 95 bears against a collar 23 provided on the lower end of said pawl. The spring 22 serves as a support for the rod 12 and for this purpose said rod is provided with a transverse pin 25 which projects laterally 100 and engages over the collar 23, the pin 25 working in a recess 26 which extends between the openings for the rod 12 and the pawl 20.

The construction above described is such 105 that the rod 12 may be manipulated to establish the engagement or disengagement of the pawl 20 relatively to the ratchet teeth 21. The rod 12 normally has an upper position, as shown in Figures 1 and 2 wherein 110

the pawl 20 is caused by the spring 22 to engage the ratchet teeth 21. However by turning the nut 16 the rod 12 may be moved axially downward to the position shown in Figure 3 wherein the pawl 20 is, by the pin 25, held disengaged from the ratchet teeth 21. At such time the drum 10 may be turned freely in either direction.

In use, one end of the clothes line being secured to any stationary support, the other end is secured by means of the posts 11 to the drum 10, the line being tightened as much as possible by hand. The nut 16 is then turned to feed the rod 12 upward and provide for the engagement of the pawl 20 with the ratchet teeth 21. The clothes are then placed on the line in the usual manner and the line is further tightened to such extent as may be necessary by turning the drum 10 by means of the handle 19 fitted to the driver 14. Such further tightening of the line by the drum 10 will eliminate any sagging under the weight of the clothes. When it is desired to take the line down the nut 16 is turned to move the rod 12 downward and thereby disengage the pawl 20 from the ratchet teeth 21. The drum 10 will thereupon be turned under the tension of the line to a position in which ready access may be had to the end of the line as secured to the posts 11 and the line may thereupon be disconnected from the drum.

The diameter of the drum 10 exceeds the width of the arms 2 and 3 and the diameter of the driver 14 from which it follows that there are no obstructions beyond the face of the drum to interfere with extending the line in any direction or at any angle which the environments of use may require. In the construction shown the pawl 20 and spring 22 are enclosed within the drum 10, thereby being protected against the elements. Said pawl and spring may also be lubricated with suitable light oil without any risk of soiling the clothes line.

In assembling the device the drum is fitted between the arms 2 and 3, the lower post 11 at such time being left off. The pawl 20, spring 22, rod 12, driver 14 and nut 16 are then fitted in position in the order named. By means of a suitable rod inserted through an opening 27 in the arm 2 the pawl 20 is held depressed to permit the insertion of the pin 25 in the rod 12, said pin being inserted through the opening provided for the lower post 11. The pawl 20 is then

released and the lower post 11 is fitted to the drum 10.

It will be understood that modifications of the construction disclosed may be resorted to within the scope of the appended claims.

Having fully described my invention, I claim:

1. A clothes line fastener and tightener comprising a supporting bracket provided with parallel arms, a drum mounted between said arms, a rod movably mounted centrally of the drum, and pawl and ratchet means to hold the drum against retrograde movement, said rod having means to control the operation of said pawl and ratchet means according to the position of said rod.

2. A clothes line fastener and tightener comprising a supporting bracket provided with parallel arms, a drum mounted between said arms, a rod movably mounted centrally of the drum, enclosed pawl and ratchet means having an element movable with the drum and a co-operating element combined with one of the arms, and means carried by said rod for controlling the operation of said pawl and ratchet means according to the position of said rod.

3. A clothes line fastener and tightener comprising a supporting bracket provided with parallel arms, a drum mounted between said arms, a rod mounted centrally of the drum for axial movement, a spring pressed pawl fitted within the drum, a connection between said rod and said pawl whereby the position of the pawl is controlled by the rod, means for adjusting the position of the rod, and ratchet teeth formed on one of the arms for co-operation with the pawl.

4. A clothes line fastener and tightener comprising a supporting bracket provided with parallel arms, a drum mounted between said arms, a rod mounted centrally of the drum for axial movement, a spring pressed pawl fitted within the drum, a connection between said rod and said pawl whereby the position of the pawl is controlled by the rod, a driver connected to the drum and projecting beyond one of the arms, the driver having an opening through which the rod extends and the rod having a threaded extension beyond the driver, and a nut mounted upon said extension and engaging the driver, the nut serving for the adjustment of the rod.

In testimony whereof I affix my signature.

WILLIAM J. KNITTER.
